(57) **CLAIM**

The ornamental design for a mixing bowl assembly comprising a separate bowl and lid, each with handles, as shown and described.

DESCRIPTION

FIG. 1 is a top perspective view of a mixing bowl assembly comprising a separate bowl and lid, each with handles, of the present disclosure;

FIG. 2 is a bottom perspective view of FIG. 1;

FIG. 3 is a first side elevational view of FIG. 1;

FIG. 4 is a second side elevational view of FIG. 1;

FIG. 5 is a top plan view of FIG. 1;

FIG. 6 is a bottom plan view of the bowl of FIG. 1;

FIG. 7 is a top perspective view of FIG. 1, with the bowl with handles shown separated from the lid with handles;

FIG. 8 is a bottom perspective view of FIG. 7;

FIG. 9 is a first side elevational view of FIG. 7;

FIG. 10 is a second side elevational view of FIG. 7;

FIG. 11 is a top plan view of FIG. 7;

FIG. 12 is a top perspective view of a FIG. 1, with the lid with handles shown separated from the bowl with handles;

FIG. 13 is a bottom perspective view of FIG. 12;

FIG. 14 is a first side elevational view of FIG. 12;

FIG. 15 is a top plan view of FIG. 12; and,

FIG. 16 is a bottom plan view of FIG. 12.

The broken lines depict portions of the article that form no part of the claimed design.
